DESIGN FOR A MEAT HOOK

Delbert A. Dick, Portland, Oreg., assignor to Phillips Products Company, Portland, Oreg.

Application February 15, 1939, Serial No. 83,000

Term of patent 14 years

To all whom it may concern:

Be it known that I, Delbert A. Dick, a citizen of the United States residing at Portland, in the county of Multnomah, and the State of Oregon, have invented a new, original, and ornamental Design for a Meat Hook, of which the following is a specification, reference being had to the accompanying drawing, forming part thereof.

I claim:

The ornamental design for a meat hook, as shown.
